Des. 240,457

Patented July 6, 1976

240,457

OPTICAL SIGHT FOR FIREARMS

Norman D. Dunlop, New Bremen, Ohio, and Glenn E. Ricket, Huntington, Ind., assignors to Precision Tool and Machine Co., New Bremen, Ohio

Filed Nov. 19, 1974, Ser. No. 525,694

Term of patent 14 years

Int. Cl. D16—06

U.S. Cl. D16—61

FIG. 1

FIG. 2

FIG. 3

FIG. 4

FIG. 5

FIG. 6

FIG. 7

FIG. 1 is a perspective view of an optical sight for firearms showing our new design;

FIG. 2 is an end elevational view thereof;

FIG. 3 is a side elevational view thereof;

FIG. 4 is a top plan view thereof;

FIG. 5 is a bottom plan view thereof;

FIG. 6 is an end elevational view thereof opposite to that shown in FIG. 2; and

FIG. 7 is a side elevational view thereof opposite to that shown in FIG. 3.

We claim:

The ornamental design for an optical sight for firearms, substantially as shown.
